UNITED STATES PATENT OFFICE.

MARK A. DREZ, OF LUBBOCK, TEXAS.

APPARATUS FOR FORMING AND VULCANIZING RUBBERIZED FABRIC AND RUBBER TIRES.

1,120,457.

Specification of Letters Patent.

Patented Dec. 9, 1914.

Application filed July 12, 1913. Serial No. 778772.

Full description.

Be it known that I, Mark A. Drez, a citizen of the United States of America, and a resident of the city of Lubbock, in the county of Lubbock and State of Texas, have invented certain new and useful improvements in Apparatus for Forming and Vulcanizing Rubberized Fabric and Rubber Tires, of which the following is a description: 5 Then, referring to the drawings, which 10 show, in detail, a part of this invention, further:

My invention relates to apparatus for forming and vulcanizing rubberized fabric and rubber tires for use on vehicle and other wheels, and my invention particularly relates to methods and apparatus for forming and vulcanizing rubberized fabric and rubber tires, which contemplate the use of apparatus 15 analogous to that shown, described and claimed in my application Serial Number 778772, filed July 12, 1913, and sometimes referred to as the "Dear old system," in which the tire structure, formed generally 20 of a plurality of plies of rubberized fabric and rubber, is shaped on a collapsible core or mandrel, inserted in a casing or mold of 25 metal, inflated in a casing or mold of metal, and then, by pressure against the inner surface of the tire structure, is expanded to the inner surface of the casing or mold, the plies of 30 rubberized fabric and rubber being simultaneously pressed together and pressed 35 firmly against the inner surface of the casing or mold by the internal expansive pressure and the tire being vulcanized while in this position.

In my application Serial Number 778772, I provide for internal expansive pressure, 40 using hydraulic or fluid means, but I have found that, while fluid pressure gives a uniform pressure, it does not produce a uniform thickness of rubberized fabric and rubber, nor tend to equalize the thick and thin inequalities produced in laying up the tire, especially those caused by laps, etc. For, if a tire body is laid on or built up with thick 45 or thin spots, there is no tendency of the fluid under pressure to force the material from a thick spot to a thin spot and thus even up the surface.

One of the objects of the present invention is to remedy this defect in tire construction by using mechanical positive pressure pro-

cessing means adjusting the tire body inside of doing the visiting fluid pressure means.

There is also danger of the fluid under pressure forcing its way into and between the layers of fabric forming the tire body, and thus preventing proper vulcanization.

One of the objects of the present invention is to eliminate all such danger by dispensing with the use of fluid under pressure, and with the tire body, the strong tendency caused by high pressure, of flying out of control against dampers.

Methods and apparatus using fluid under high pressure in movable parts are necessarily very expensive owing to the requirements, such as packed joints, for preventing the leakage or escape of the fluid under pressure.

One of the objects of the present invention is to lessen the expense by using mechanical means in the moving parts within the mold in place of the fluid pressure means.

One of the objects of the present invention is to improve the shape of rubberized fabric and rubber tires by forming and vulcanizing them in such shape that when inflated on the wheel rim, the stress or strain of inflation is partly transferred from the fabric in the vicinity of the tread to the fabric in the sides of the tire.

In the drawings: Figure 1 is a vertical section on approximately the middle line of a tire forming and vulcanizing apparatus constructed in accordance with my invention and showing the position of parts before pressure is applied to the tire body; Fig. 2 is a transverse section of a part of same on the line 2-2 of Fig. 1; Fig. 3 is a similar view on the line 3-3 of Fig. 1; Fig. 4 is a vertical section somewhat similar to Fig. 1 and showing the position of parts after pressure is applied to the tire body; Fig. 5 is a detail section of certain valves shown in Figs. 1 and 4; Fig. 6 is a detail section of a spline or key connection between parts of an expandable core; Fig. 7 is a horizontal section on the line 7-7 of Fig. 1 parts being broken out for purposes of illustration; Fig. 8 is a detail of a part of an expandable core before expansion; Fig. 9 is a detail of a centering block; Fig. 10 is a vertical section of a modified form of the forming and vulcanizing apparatus and showing the position of parts after pressure

is applied to the tire body; Fig. 11 is a detail of a part of an expansible core after expansion; Fig. 12 is a plan view of a collapsible, expansible core, assembled and covered with a tire body, parts being broken away for purposes of illustration; Fig. 13 is a transverse section through a casing or mold containing a preferred form of tire and a core for same; the dotted lines indicating the position of the core before pressure is applied and the full lines indicating its position after pressure is applied; and Fig. 14 is a transverse section of a tire applied to a rim according to my present invention, the dotted lines indicating the position of the tire body before inflation and the full lines indicating the position of the tire body after inflation.

20 is the cylinder of a hydraulic press or 20 ram, containing a plunger 21 having a large flat-topped head 22 into which is countersunk an auxiliary cylinder 23, the cylinder being open at its upper end, closed by a bottom 24 at its lower end, and containing 25 a piston head 25 provided with suitable packing 26 and a countersunk upper face 27. 28 and 29 are respectively larger and smaller pipes establishing communication between chamber 30 of the cylinder 20 at one end 32 and inlet and outlet valve casings 31 and 32 respectively at the other end, both valve casings leading to the chamber 33 in the cylinder 23. The valves 34 and 35 are both spring seated, the spring 36 of the former 35 being heavier than the spring 37 of the latter, so that the valve 34 opens in response to a heavy inward pressure toward the cylinder chamber 33 and the valve 35 opens with a very light outward pressure from the cylinder chamber 33. In this construction, the pipes are fitted tight to the lower end of the plunger 21, fitted tight to the valve casings, and packed where they pass through the intermediate partition 38, the connections between the valve casings, and the bottom 24 of the cylinder 23 being preferably made tight, although this is not essential. It is desirable that the cavity 39 of the plunger 21 be kept free from fluid or pressure for reasons of economy in operating the apparatus. 40 is the fluid inlet to the chamber 30. In the operation of this part of the apparatus a preliminary pressure (of for instance 100 pounds) will raise the plunger 21, and a heavier pressure will open valve 34, and raise piston head 25. A reduction of pressure will close valve 34, allow valve 35 to open and allow piston head 25 to descend, and a further reduction of pressure will allow the plunger 21 to descend.

41 is the bottom, 42 the side and 43 the cover of a vulcanizer pot having a vulcanizing chamber inclosing the plunger head 22 and the two part tire molds 44 during the

operating of the apparatus. The cover is secured against upward movement with respect to the casing or remainder of the vulcanizing chamber by the bayonet joints 45, a slight rotary movement of the cover 43, 70 with respect to the rest of the vulcanizing chamber being sufficient to lock or unlock the joint in the usual manner.

46 is an eye by which power raising devices may be attached to the cover for the 75 purpose of convenient handling of it.

47 are the usual lugs to assist in convenient handling of the molds 44.

In Fig. 10 I have shown a modification in which the cylinder 48 is mounted upon 80 instead of within the plunger head 22, being secured thereto by fastenings 49, a riser 50 being laid on the plunger head 22 to compensate for the difference in elevation of the piston head 25. Communication between the chamber 30 and the chamber 33 in this modification is established by means of holes 50 and 51 in the plunger head 22, valve casings 52 and 53 fitted to the plunger head 22 about the holes 50 and 51, and pipes 52 and 29 coupled to the valve casings 52 and 53 respectively, the lower ends of the pipes being secured to the lower end of the plunger by packed nuts 54. This modified form is especially intended for instances 95 where it is desired to use an old form of press without making extensive changes.

The tire molds are placed one above the other on the plunger head 22 and the upward movement of the plunger clamps the 100 molds in fixed relation to the vulcanizing chamber.

Corresponding with each mold 44 and situated one above the other upon the countersunk upper face 27 of the piston head 25 105 are centering riser blocks 55, the precise shape of each block especially as to its height and proportions depending on the size and design of the tire mold and tire to which it corresponds. In common the 110 blocks have a solid lower part 56, and upwardly projecting approximately cone shaped upper central part 57, and radiating pairs of guide flanges 58, preferably four pairs, each pair of guide flanges 58 guarding a slot 59 having an inclined rear face 60 and inclined bottom face 61, and intermediate niche 62, in which niche the inner end of a spring arm 63 having a spring 64 at its outer end may loosely rest. It is obvious 120 that the raising of the piston head 25 will cause a corresponding raising of the blocks 55, resulting in the outward radial movement of the arms 63. The arms 63 may be of curved spring metal, obviating the use of 125 the springs 64, or they may be used without springs.

Referring more particularly to Figs. 7, 8, 11 and 12, 65 is a laminated tire structure laid up or built on a core or forming man- 130

ired comprising long sections 66 and short, approximately triangular, sections 67, the long and short sections alternating and being secured together by tap screws or bolts 68, and splined, mortised or keyed together by keys 69 and slots 70, the keys being preferably secured to the long sections by countersunk screws 71. Each section has an outer cross sectional contour corresponding to the inside shape of the tire, upper and lower offset surfaces 72 corresponding to the bottom of the clencher parts of the tire, rearwardly extending parts 73 conforming to an adjacent part of the inside face of the two part mold, and edge lips or flanges 74 serving as stops to limit the outward radial movement of the section with respect to the two part mold. The sections are preferably hollowed on the inside, the triangular sections being provided with recesses 75 for the reception of the springs 61 or the outer ends of the grooves 63. The sections are preferably bolted together until the tire is laid up or built thereon, the tap screws being removed when the arms 63 are to be inserted. It is obvious that the outward radial movement of the arms 63 causes the triangular sections 67 to move radially outward, pressing the longer sections 66 radially outward, the tire being thus moved bodily toward and against the inside of the two part mold in a perfect circle. It is also obvious that the triangular sections 67 move radially outward about twice as fast as the longer sections 66 in order to reach the tire at the proper time, as the longer sections, while moving radially, are also moving at an angle to the triangular sections and away from each other.

Either solid or laminated tire structures may be treated with the present apparatus, practically the only essential being that the inside of the tire be approximately U-shaped in cross section.

In Figs. 1 and 4 I have shown an ordinary proportioned tire of about thirty-six inches in diameter, surmounted by a long clencher tire of about the same diameter, symmetrized in turn by an ordinary proportioned thirty inch tire. The relative distances of the niches from the center of the blocks 55 and the relative heights of the lower solid parts of the blocks offset the difference in diameters and thickness of the tires and tire molds, so that any of the same length may be used in every case.

The preferred form of tire is seen in Figs. 13 and 14, the tire being constructed with outer rubber tread 80 and inner laminated structure 81, secured by wires 82 in substance accord with my application Serial Number 829322, filed April 4, 1914, the core sections being substantially semi-circular on their intermediate outer faces 83, having slightly flaring side parts 84, offsets 85 and flanges or lips 86. The position of the core section prior to pressure is shown in short dash lines in Fig. 13 and it is obvious that when moved to the position indicated in full lines the tire is pressed outward against the inner face of the two parts 87 and 88 of the mold, and that the clencher parts of the tire are also pressed sideways as well as forward, so that a compacting pressure is laid on all points. When placed in the rim and inflated the tendency of the tire structure is to assume a more nearly circular shape resulting in a change of shape from that indicated by the short dash lines in Fig. 14 to that indicated in full lines in the same figure, the middle portion 80 of the tread moving inwardly and compressing the face of the tread and the side parts of the tire moving outwardly.

My raw tire is laid up or built on a core or forming mandrel, the circumferential or larger diameter of which is slightly greater than the inside of the tread part of the tire when the tire is inflated and slightly smaller than the cross section of the same part. The mold is correspondingly constituted, so that when the tire is vulcanized under these conditions and inflated on the wheel rim, the tire enlarges itself in cross section, somewhat flattening the cross sectional contour of the tread of the tire and at the same time reducing the larger diameter or circumference of the tire, thus compacting the rubber of the tread and slackening the tension of the threads in the direction of the larger circumference of the tire, throwing the inflation tension on the cross section circumference of the tire, the U shape of the forming mandrel causing the beads or inner edges of the tire to be wider apart than when inflated, so that when they are pressed toward each other in mounting the tire in the rim, the fabric of the inner half of the tire, in the direction of both circumferences, is relaxed somewhat in its tension, throwing more tension on the rubber reinforcement of the sides of the tire, thus producing loose inner plies of fabric circumferentially of the tire, where so called "blow-outs" are most common. This part of the tire is however seldom punctured, so that I produce by this method a tire that has slack inner plies on the immediate tread, tensioned plies circumferentially of the knuckles on each side of the tread, and loose inner plies between the knuckles and the rim, all of which are desirable features in a tire.

The preferred method of operating my apparatus is as follows: The collapsible core or forming mandrel is assembled in its contracted condition as shown in Fig. 12, the parts or sections being held together by the tap screws 68. The core or mandrel is then suspended on a four armed spider center as is commonly used by tire builders. The tire is then laid up on the mandrel in any de-

sired way, preferably in the manner shown in my application Serial Number 829522, and of the shape shown in Fig. 13 of this application. The tap screws are removed the mandrel being retained in shape by the raw tire which surrounds it. The two halves of the two part mold are placed around the raw tire, pressed together and placed on the plunger head of the hydraulic press within the vulcanizing pot. The center block and spring arms are inserted as shown in Fig. 1, a second mold containing a tire is placed on top of the first mold, a second center block is placed on the first center block and its arms inserted, this process being repeated until the capacity of the pot is reached. The pot is then closed, the molds pressed around the tires with any desired predetermined pressure by raising the plunger head until the molds are clamped between it and the cover of the pot, and for any predetermined time, during which time steam may or may not be let into the pot around the molds. At a predetermined time the pressure in the hydraulic cylinder may be increased, opening the valve 34 and permitting the fluid to pass into chamber 33 raising piston head 25, the center blocks 35 rising and spreading the arms 63 radially, and pushing outwardly the triangular sections 67, pressing the longer sections 66 radially, expanding the core or mandrel to a complete perfect circle, thus expanding the raw tire, tensioning the fabric strands thereof, and compacting and shaping the rubber tread and side parts of the tire against the inner walls of the molds, in which position the parts are firmly held during vulcanization. After vulcanization the pot is opened up by removing the cover, the spring arms and center blocks are removed, the tire molds lifted out, the tires removed from the molds, the collapsible cores removed from the tires, and the tires stored or applied to the rims of the wheels. The collapsible cores, molds, center blocks, arms and vulcanizing pot are at once available for further service in making additional tires.

While I have shown my piston head 25, operated by automatic means comprising fluid under pressure from the ram cylinder, yet, in some cases, I may conduct the fluid under pressure to the cylinder 23, through a coiled pipe and fluid receiver such as shown in my application Serial Number 778772. The vulcanizing steam carried in the vulcanizing chamber may have any desired pressure and temperature. I have shown my core mandrel in four segments and four wedge pieces, but other divisions of the core may be made if found advisable. The drawings show the two faces of the wedge pieces to be at an angle of about 60° to each other, but the angle could be more or less. The hollows or grooves in the core could be filled with

asbestos or other material which is a non-conductor of heat. I show only a smooth tread tire, but any kind of anti-skid tread could be formed thereon, no particular claim being made to the style of tread or mold adjacent the tread.

The combined metal and rubberized fabric tire shown in Fig. 14 fits onto a wheel like an ordinary demountable rim. In fact the metal part might well be an ordinary rim of approximately the shape shown.

Having thus described my invention the following is what I claim as new therein and desire to secure by Letters Patent:

1. The combination of a vulcanizing chamber, a mold, a contractile, expandable and collapsible sectional core having triangular sections, a centering riser block formed with radial guide flanges providing slots and radial arms having their inner ends located in the slots and their outer ends connected with the triangular sections of the sectional core.

2. The combination of a mold, a contractile, expandable and collapsible sectional core having triangular sections, a centering riser block formed with radial guide flanges providing slots, each slot having an inclined rear face, an inclined bottom face and an intermediate niche, and radial arms having their inner ends located in the slots and their outer ends connected with the triangular sections of the sectional core.

3. The combination of a vulcanizer pot, a mold confined within the vulcanizer pot, a contractile, expandable and collapsible sectional core and mechanical means for expanding the core within the mold.

4. The combination of a vulcanizer pot, a mold confined within the vulcanizer pot, a contractile, expandable and collapsible sectional core, a mold moving means on which the mold is carried and mechanical means for expanding the core within the mold.

5. The combination of a vulcanizer pot, a mold confined within the vulcanizer pot, a contractile, expandable and collapsible sectional core, a depending cylinder, a plunger having a head on which the mold is carried, mechanical means connecting the mold with the plunger, and mechanical expanding means connecting the sectional core with the plunger.

6. The combination of a vulcanizer pot, a mold confined within the vulcanizer pot, a depending cylinder, a plunger having a head on which the mold is carried and a piston, and mechanical expanding means connecting the sectional core with the piston.

7. The combination of a vulcanizer pot, a mold confined within the vulcanizer pot, a contractile, expandable and collapsible sectional core, a depending cylinder, a fluid operated plunger having a head on which

- the mold is carried, and an auxiliary cylinder, a piston in the auxiliary cylinder, pipes mounted in the plunger, having inlet and outlet valves and forming communication 5 between the depending cylinder beneath the plunger and the auxiliary cylinder of the plunger and mechanical expanding means connecting the sectional core with the piston.
- 10 8. The combination of a vulcanizer pot, a mold confined within the vulcanizer pot, a contractible, expansible and collapsible sectional core, a depending cylinder, a fluid operated plunger having a head on which 15 the mold is carried and an auxiliary cylinder, a piston in the auxiliary cylinder, differential pipes mounted in the plunger having differential inlet and outlet valves and forming communication between the depending cylinder beneath the plunger and the auxiliary cylinder of the plunger and mechanical means connecting the sectional core with the piston.
9. An apparatus for forming and vulcanizing rubberized fabric and rubber tires comprising a vulcanizer pot, a mold confined within the vulcanizer pot, a contractible, expansible and collapsible sectional core having triangular sections, mold supporting means having a piston, means for 20 operating the piston, a centering riser block seated on the piston, formed with radial guide flanges providing slots and radial arms having their inner ends located in the slots and their outer ends connected with the triangular sections of the sectional core.
10. An apparatus for forming and vulcanizing rubberized fabric and rubber tires comprising a vulcanizer pot, a mold confined within the vulcanizer pot, a contractible, expansible and collapsible sectional core having triangular sections, mold supporting means having a piston, means for 25 operating the piston, a centering riser block seated on the piston, formed with radial guide flanges providing slots, each slot having an inclined rear face, an inclined bottom face and an intermediate niche, and radial arms having their inner ends located in the slots and their outer ends connected with the triangular sections of the sectional core.
11. An apparatus for forming and vulcanizing rubberized fabric and rubber tires, comprising a vulcanizer pot, a mold confined within the vulcanizer pot, a contractible, expansible and collapsible sectional core having triangular sections, mold supporting means having a piston, means for 30 operating the piston, a centering riser block seated on the piston, formed with radial guide flanges providing slots, each slot having an inclined rear face, an inclined bottom face and an intermediate niche, and radial arms having their inner ends located in the slots and their outer ends connected with the triangular sections of the sectional core.
12. The combination of a vulcanizing chamber, a mold, a contractible, expansible and collapsible sectional core, a centering riser block formed with guide flanges providing slots and radial arms having their inner ends located in the slots and their outer ends connected with alternate sections of the core. 35
13. In apparatus for forming and vulcanizing rubberized fabric and rubber tires, a vulcanizing chamber, mold moving means operable within said chamber, a mold containing a tire, supported by said mold moving means, a fluid operated cylinder and piston carried by said mold moving means, and an expansible core within the tire and operable by said cylinder and piston. 40
14. In apparatus for forming and vulcanizing rubber tires, a vulcanizing chamber, a mold confined in said chamber incasing a tire within which is an expansible mandrel, the expansion of said mandrel being controlled from the exterior of the vulcanizing chamber. 45
15. An apparatus for forming and vulcanizing plastic articles, comprising a vulcanizing chamber, a mold adapted to receive a partially formed article built up on a contractible, expansible and collapsible core, and mechanical means for completing the forming of the article by expanding the core outwardly toward the inner faces of the mold, the article being vulcanized in the expanded position. 50
16. An apparatus for forming and vulcanizing rubber articles, comprising a vulcanizing chamber, a press head within the chamber, a mold carried by the press head, and held against the cover of the chamber, an expansible core mandrel within the mold and operable by arms leading downwardly and outwardly from sections of the core mandrel, toward a common center, and supported on a vertically operable piston head and means for heating the vulcanizing chamber. 55

WALTER ELLWOOD ALLEN.

Correction in Letters Patent No. 1,120,453.

It is hereby certified that in Letters Patent No. 1,120,453, granted December 8, 1914, upon the application of Mark A. Dees, of Lubbock, Texas, for an improvement in "Apparatus for Forming and Vulcanizing Rubberized Fabric and Rubber Tires," an error appears in the printed specification requiring correction as follows: Page 5, line 87, for the word "chambers" read *chamber*; and that the said Letters Patent should be read with this correction therein that the same may conform to the record of the case in the Patent Office.

Signed and sealed this 5th day of January, A. D., 1915.

[SEAL.]

R. F. WHITEHEAD,

Acting Commissioner of Patents.
